DESIGN FOR ARTIFICIAL LEATHER

Joseph A. Puppo, Crestwood, N. Y., assignor to
E. I. du Pont de Nemours & Company, Wilmington, Del., a corporation of Delaware

Application March 4, 1937, Serial No. 67,978

Term of patent 14 years

To all whom it may concern:

Be it known that I, Joseph A. Puppo, a citizen of the United States and a resident of Crestwood, in the county of Westchester and State of New York, have invented a new, original, and ornamental Design for Artificial Leather, of which the following is a specification, reference being had to the accompanying drawing, forming a part thereof.

The figure is a plan view of a piece of artificial leather showing my new design.

I claim:

The ornamental design for artificial leather, substantially as shown.

JOSEPH A. PUPPO.
